① Philip the apostle

A native of Bethsada near Lake Galilee, one of the twelve disciples of Jesus. Before becoming a disciple of Jesus, he is believed to be a disciple of baptism John with Andre. He led Nathanael to the Lord, and, as seen in Oh's transfer, he was rational and quick to calculate, while timid and passive. He witnessed the resurrection of Jesus personally and received the Holy Spirit in the attic of the Pentecost. After the persecution of Stefano, he preached to Samaria, where he joined Simon Mags, and baptized an Ethiopian spectator in Gaza, south of Jerusalem. In his later years, he is said to have been martyred in Hierapolis while serving in Bruckia, Asia. According to Eusebius, a fourth-century church history was buried with four daughters in Hierapolis, Asia.

Matthew

He is the son of Alfa, meaning "a gift to Jehovah." His real name was Levi, from Gavanaugh, from Seri, an official who had been scorned and rejected by the people, and he was a very wealthy man. At the call of Jesus, he became one of the 12 disciples. If you look at his track record, he was called by Jesus and became a disciple while he was doing customs work at the 1 Gavanaugh Customs. After becoming a disciple, he invited his fellow Seri and many other disciples to hold a big feast and to testify his remorse. On the day of the Pentecost, we experienced the grace of the Holy Spirit in the attic of 3maga. 4 For Jews who are familiar with the Old Testament, the Gospel of Matthew was written to convey the message of God's salvation.

24 James

He is one of Jesus' three representative disciples (Pedro, John, and James). As a fiery personality, he was scolded when he pleaded with Jesus to set fire in the sky and destroy it when Samaritan rejected him. He was accompanied by Jesus when he was saving the Byeolsan and Yairo's daughter and praying in the Garden of Getsemane. He believed with his brother John that he should be the political Messiah of Jesus and sought worldly status. He ran away just like other disciples when he was captured, but after meeting the resurrected Jesus, he was killed by Herod Agripa I, who became the first martyr of the twelve apostles.

27 Jeremiah

He was so sensitive that he was called "the prophet of tears." In particular, he had no choice but to prophesy internally in conflict and lamentation between the God of righteousness to judge sin and the insensitive people who did not realize its seriousness. In this respect, Jeremiah is also suggested as a forerunner of Jesus Christ in the new drug. Meanwhile, Jeremiah was called a prophet at a young age (about 20 years old), and his personal happiness had to be left behind, such as not being able to marry at God's command and being ostracized by those close to him. In addition, he was misunderstood as a false prophet by prophesying the fall of his country and urging King Babylon to serve, and spent a life of pain and lamentation, imprisoned and threatened by his enemies as well as mental and physical pressure.

31 David

The second king of ancient Israel. The ritual system was established and Judaism was established around Jerusalem. He also gained fame as a poet, and much of the Old Testament's poems were written by David. David had been a strong man since he was a boy and had the makings of a warrior. When Samuel the prophet heard of him, he brought him to the royal palace of Jerusalem and made him king Saul's successor. When King Saul died, David was appointed king of Judaism, and he attacked Zion (Ophel Hill), an impregnable fortress, to unify Israel and change its name to David. What is famous for David's story is that in the war against the Philistines, God's power was used to bring down Goliath the giant with a water millstone.

34 Paulos / Paul

Almost the same time as Jesus, he was born into a Jewish family in Darth, the capital of Gileadie, So Asia. Growing up as a member of the Pharisei faction eager for the law, he persecuted Christians who were Jewish and neglected the law, who one day suddenly experienced repentance and since then served as evangelists of Christianity, especially to preach the gospel to strangers. Originally engaged in evangelism at the Antioch Church in Syria, and the Jerusalem Conference opposed the move to impose a duty of law-abiding on the Outlander believers as representatives of the Antioke Church. Paul's faith, which is only justified by faith, later greatly influenced the history of Christianity. His evangelical work during the congregation also set an example in the Church of Christ.

33 Solomon

He is the third king of the Kingdom of Israel and is known as the "King of Wisdom" for his wise judgment and determination. He was born in Jerusalem and was born in David, the father king, and in Bathsheba. "and Bathsheba was married to Hittite's mercenary, but she became David's wife and gave birth to Solomon." David, who unified Israel, had several sons, who fought between sons over the throne, and Solomon, who defeated his brothers, succeeded him as king of Israel. He defeated his opponents and put his efforts into external peace to achieve the heyday of the kingdom. Among the Old Testament books, Alga and Zamun are said to be his works, and it can be seen how wise Solomon was to judge the two mothers fighting over one baby.

Noah

He listened to God's warning that he would judge mankind by great flood at 480 and obeyed God's instructions for 120 years, warning of God's judgment and urging repentance. But no one repented, and in the end, Noah and eight other family members (Noah, wife, three sons and three daughters-in-law), seven pairs of animals and two pairs of unclean beasts entered the ark to prepare for the flood. A heavy flood occurred at Noah's age of 600, and for 40 days the rain continued to fill the ground with water for 110 days. And 220 days later, when Noah's ark came to Mount Ararat, Noah came out of the ark and built a altar and offered a thank-you service to God. At this time God gave us a rainbow covenant that we would no longer judge mankind with water.

54 Elijah

Elijah the prophet is an important figure in the Old Testament. He was a man of both courage and faith, and confronted head-on against such powerful enemies as King Ahab and Queen Jezebel of Israel. Elijah is bloodless and fights with 450 Baal followers. He leads the crowd into a crisis, saying that the people of Israel should choose between God and Baal. Baal prophets cut their bodies with knives while dancing fanatic dances, but nothing happens. When Elijah appealed to the God of Israel, he sent down the fire and burned the offerings of the altar. Shocked, the people of Israel shout that they believe in God and execute the Baal prophets. Finally, the long drought ends. When King Ahab returns in a tram, Elijah walks past him.
